UNITED STATES PATENT OFFICE.

CHARLES HUGH MARTIN, OF LOS ANGELES, CALIFORNIA, ASSIGNOR OF ONE-HALF TO
ANGELO FREDIANI, OF LOS ANGELES, CALIFORNIA.

VENTILATED PRINTING-PRESS ROLLER.

Application filed August 9, 1922. Serial No. 580,639.

To all whom it may concern:

Be it known that I, CHARLES HUGH MARTIN, a citizen of the United States, residing at Los Angeles, in the county of Los Angeles and State of California, have invented a new and useful Ventilated Printing-Press Roller, of which the following is a specification.

In the operation of printing presses, it frequently occurs that the friction and pressure upon the inking roller heats the composition of such roller to such an extent that it becomes loosened from the core, or melts down, causing much expense and loss of time.

An object of this invention is to avoid this difficulty and to thereby greatly increase the life of the roller.

Another object of the invention is to minimize the amount of composition required for the printing roller of a printing press.

A further difficulty with printing press rollers as heretofore constructed arises from this liability to sag in the middle and an object of this invention is to correct this difficulty, and avoid such sagging.

The invention practically includes a printing press roller having a hollow core, and in the preferred form such core is ventilated and air is passed therethrough.

A further object of this invention is to provide a practical inking roller with means for forcing air through the core to cool it.

Inking rollers for printing presses comprise a rigid core and are completed by inserting such core into a cylindrical mold into which composition is then poured to form upon the core, the ink carrying surface of the roller and such core is provided with a flange to fit the mold and form a bottom therein, upon which the composition is supported in the mold, and an object of this invention is to provide means whereby such composition may be molded and remolded on a hollow core having means that will cause air flow through the core when the roller is revolved. In the work of molding composition onto the core, it is desirable that the flanged end of the core be inserted into the mold and that the flange fit the mold and form a bottom therefor. It is preferable that the draft producing means be so constructed as to extend beyond the rim of the flange during operation so as to

drive away the air external to the flange and thus produce a pressure drop at the outlet end of the draft core; and in order to practically meet the requirements I hinge vanes inside a ventilator in the form of a lantern wheel having rungs in two circular series, the outer rungs of which form stops for vanes hinged to the inner rungs, the stops being so arranged that the vanes may be swung inside the circle of the flange when at rest, and will swing to project outside such circle when the roller is revolving.

Other objects, advantages and features of invention may appear from the accompanying drawing, the subjoined detail description and the appended claims.

The invention may be carried out in various ways and I do not limit myself to specific forms of construction.

The accompanying drawing illustrates the invention in a form I at present deem preferable.

Fig. 1 is a fragmental perspective view of the metal parts of an inking roller constructed in accordance with this invention, 80 omitting the roller composition.

Fig. 2 is a fragmental axial section of a ventilated printing roller constructed in accordance with what is shown in Fig. 1.

Fig. 3 is a cross section on line x^3-x^4 , 85 Fig. 2 cutting through the ventilator or draft wheel and looking in the direction of the upper arrow.

Fig. 4 is a sectional elevation on line x^3-x^4 , Fig. 2, looking in the direction of the lower arrow.

Fig. 5 is a side elevation in reduced scale, of the roller shown in Figs. 1 and 2.

The journals or stub shafts 1 and 2 may be of any usual construction and may be made from sections of cylindrical rods of cold rolled steel. The tubular main shaft or hollow core 3 of the roller is provided with a longitudinal bore α , and is connected at one end to a hollow section 4, that forms a connection between the main shaft 2 and the hollow core 3 and is perforated near the stub shaft by orifices 5, which allow air to flow through the bore to the open end 6 near the journal 1.

The core 3 is provided at its open end 6 with a flange 7 to give strength and rigidity to the open end of the core.

The composition 8 is of the usual well known character and forms a cylinder, the

105

110

periphery of which is about flush with, or of greater diameter than the periphery of the flange 7. A flange head 9 to which the stub shaft 1 is fixed, corresponds in diameter to the flange 7, and is connected thereto and spaced apart therefrom by suitable means as outer and inner rungs 10 and 11. The rungs 10 are spaced equidistant apart at the periphery of the flange 7, and head 9, and the rungs 11 are spaced equidistant apart in a circle arranged inside the circle of the outer rungs. The inner rungs 11 are arranged midway between the radii on which the outer rungs 10 are centered. A ventilator is thus formed, closed at one end by the imperforate head 9 and opening from the bore. It is provided with vanes 12 pivotally mounted on the inner rungs 11 and of sufficient width to stop against the outer rungs 10 when at rest, and to project beyond the head 9 and flange 7 when swung by centrifugal force into position radial to the axis of rotation.

By this arrangement the vanes are supported in retracted position and are free to swing out for the purpose of creating a vacuum pressure drop inside the hollow core 3 when the roller is revolved with sufficient speed in either direction.

The flange 7 and head 9 are considerably greater in diameter than the core 3, so that the draft from the ventilating orifices is forced through the core and the reel by the pressure drop created by the vanes.

In practical operation the vanes 12 are brought from the tangent position shown in full lines in Figs. 3 and 4 to the radial position indicated by dotted lines in Fig. 3 as the centrifugal force set up by the rotation 40 of the roller increases. The force of the draft through the hollow roller core is relative to the space between the flanges and the projection of the vanes beyond the circumference of said flanges and the speed with which the roller is rotated.

The draft through the roller will be from the inlet 5 to the periphery of the path of the fans formed by the revolving blades or vanes 12, and the projecting portions of the blades produce the required pressure drop to cause a flow of cooling air through the roller shaft or core.

The inlet end of the hollow core or shaft is reduced and the inlets 5 are closer to the axis of the roller than the periphery of the flanges or heads 7 and 9 so that the cooling air may readily enter the roller at that end to supply the outflow at the ventilator formed by the heads or flanges 7 and 9, the connecting rungs 11 and 10 and the vanes 12.

Inking rollers are required to be of a

proper thickness; and by making the roller core hollow, I have effected a saving of composition without reducing the efficiency of the roller; and at the same time I have reduced the weight and increased the rigidity of the roller; and by providing for a longitudinal draft and an internal cooling of the roller I have given the roller greater life and made it practically free from melting down under high-speed operation, or long service.

I claim.

1. A printing press roller having a hollow core open at one end and perforated at the other end to allow flow of air therethrough, and means at such other end to produce pressure drop for the purpose of causing a flow of air through the roller.

2. A printing press inking roller comprising a hollow core open at both ends and provided at one end with means for producing pressure drop.

3. A printing press inking roller having an open ended tubular core in combination with vanes pivotally arranged to produce pressure drop at one end of the core.

4. A printing press roller comprising a hollow core open at its ends; a flange fixed to one end of said core; a flange spaced from and secured to said fixed flange; rungs between the flanges; vanes on said rungs; and stops to support the vanes in a retracted position; said vanes being adapted to swing out under centrifugal force for producing a pressure drop to cause air to flow through said hollow core.

5. A hollow roller provided with ventilating means comprising hinged vanes projecting beyond the periphery of the roller when radial to the axis of the core; the inlet end of the roller being reduced so that the air flows in close to the axis where the peripheral speed is low and is thrown out at the other end where such speed is higher.

6. A roller comprising stub axles, a tube having openings at its ends; means connecting the tube to the stub axles; and air expelling means in one of such connections.

7. A roller provided at one end with a ventilator and a fan to expel air therefrom; said roller also having a bore connected with said ventilator and adapted to conduct air through the roller to the ventilator to cool the roller.

In testimony whereof, I have hereunto set my hand at Los Angeles, California, this 3rd day of August, 1922.

CHARLES HUGH MARTIN.
